UNITED STATES PATENT OFFICE.

FREDERICK W. LINAKER AND THEODORE M. BRUBACK, OF DUBOIS, PENNSYLVANIA.

TUBE CLEANER.

Application filed March 10, 1920. Serial No. 364,614.

To all whom it may concern:

Be it known that we, FREDERICK W. LINAKER and THEODORE M. BRUBACK, the former a subject of the King of Great Britain, and the latter a citizen of the United States of America, both residing in Dubois, in the county of Clearfield and State of Pennsylvania, have invented certain new and useful Improvements in Tube Cleaners, of which the following is a specification.

This invention relates to improvements in tube cleaners and to combinations of such cleaners with tube systems, more particularly the tube system of a fire tube boiler, and aims to provide improvements therein.

The present invention provides means for inducing or superinducing a strong draft or current through a tube or tubes, so that the draft or current induced through said tubes will carry with it deposited soot and other extraneous matter deposited or lodged within said tubes. The draft-inducing means comprises jet nozzles introduced within the tubes, to which nozzles a fluid under pressure, preferably steam, is conducted through suitable pipes, and the nozzles direct the pressure-jets axially or parallel with the axes of the tubes, so as to induce a strong flow of gases within the tubes.

The invention further provides parts and arrangements providing for the effective construction and functioning of the invention, as will be hereinafter more fully set forth.

An embodiment of the invention is illustrated in the accompanying drawings. In said drawings,—

Figure 1 is a vertical sectional view of the front end of a return tube boiler, showing the invention applied to and combined with said boiler.

Fig. 2 is a cross-section on the line 2—2, Fig. 1.

Fig. 3 is a detail view, partly in section, showing one of the cleaner elements.

In said drawings, numeral 1 designates the tube system, and numeral 2 the cleaner.

The cleaner comprises one or more elements 3 adapted to project within the tubes of the tube system, preferably to a limited extent. Where there are a plurality of these elements 3, they are preferably connected to one or more headers 5, and these headers may in turn be connected to a supply pipe

or pipes 7, 7' conducting compressed fluid, preferably steam from the boiler, to said headers.

For convenience in setting up, replacement, etc., the portion of the supply pipe carrying the headers is made detachable, conveniently by a union 9. Furthermore, for convenience in gaining access to individual tubes of the tube system, the headers are detachably connected to the supply pipe or pipes 7, 7' by means of unions 11, for example.

The element or elements 3 are provided with jet-forming devices or jet nozzles 15 adapted to project a jet of compressed fluid (steam, for example) toward the outlet end of the tube, whereby a draft or current of air, or combustion gases, may be induced (or superinduced upon the draft of the chimney) in such manner that the said draft or current of air or gases will blow or carry along with it soot and other extraneous particles from within the said tube.

The jet nozzles 15 are expanding or accelerating nozzles, being formed, as clearly shown in Fig. 3, with a contracted inner end, and expanding thence to a larger outer end, so that the steam or fluid under pressure is held under substantially supply pipe pressure until it enters the nozzles, and accelerates in passing through the nozzles, so as to attain a high velocity. The nozzles are directed with their axes parallel to the pipes 3 and to the boiler flues, so that the jets issuing therefrom are parallel to and as nearly as possible coincident with, the axes of the flues, and are effective to induce a powerful flow of gases through the flues in the direction of the jets.

The jet nozzle 15 which is inserted within each of the fire tubes, is best located toward the outlet or exit end thereof, and is arranged to discharge the jet of steam or other compressed fluid towards such outlet end, so that the jet shall induce an accelerated or intensified flow of gases (being fire gases or air, or a mixture thereof) in the direction of the normal draft. It is characteristic that a jet of fluid under pressure is discharged in a direction parallel to the axis of the tube instead of angularly thereto; the effect is to utilize the pressure jet most effectively to induce a strong flow of gases through the tube, as contradistinguished from the utilization of

the jet to itself scour the inner surface of the tube. By reason of the location of the nozzle toward the outlet end of the tube, any scouring by the jet would be confined to the portion between the nozzle and the outlet end, but since the effective action is that of the induced blast of gases through the tube, this action extends uniformly throughout the length of each tube.

- 10 It will be obvious that the elements may be inserted from either end of the tube, but they are preferably inserted, as here shown, from the end of the tube which is at the exit of the draft or current of flue gases 15 (viz, the ordinary draft), through said tube or tubes, and under such circumstances the element need extend but a short distance within the tube. Moreover, where the element is inserted from the exit end 20 of the tube, the jet-forming means is arranged so as to project a backwardly directed jet, that is, a jet toward the end of the tube from which the element enters. The jet-forming means is conveniently 25 formed by attaching a return bend 13 to the element 3, and providing said return bend with a suitable jet-forming nozzle 15.

The dimensions of the steam pipe, nozzle and return bend in a plane transverse to 30 the boiler tube or flue are so small in proportion to the transverse area of the tube that their presence in the tube does not materially obstruct the draft; hence they may be mounted permanently in place without detriment.

For convenience in installation, in a return tube boiler, the elements and headers are conveniently placed within the smoke box 17, these smoke boxes usually being 35 provided with hinged doors which can be opened to expose the entire tube sheet 19 of the boiler.

The supply of compressed fluid to the elements is governed by suitable valves 21, 21', 40 in the pipes 7, 7'.

Inasmuch as the reaction from the backwardly-projected jets is considerable, the header, or other part to which the element is connected, is preferably provided with 50 suitable spacing or supporting means 23, said means conveniently being, as here shown, a simple foot bearing on the tube sheet, against which the header bears when acted on by the reactive force of the jet.

55 As clearly shown in Fig. 2, the elements are divided into two groups, those of one group being fed by the pipe 7 under control of valve 21, and those of the other group by pipe 7' under control of valve 21'. As here shown, the former group of elements enters the fire tubes which appear at the right of the middle of the boiler; while the latter group are applied to the fire tubes to the left thereof. This arrangement enables the cleaning means to be op-

erated either (1) by simultaneously opening both valves, so that all the fire tubes are blown together, with the same effect as if all the drop pipes 5 branched from one header controlled by one valve; or (2) by 70 opening the valves 21, 21', one at a time, whereby to blow the group of tubes on one half of the boiler at one time, and those on the other half at another time. The grouping of the tubes in halves is illustrated as a suitable and, probably in most cases, the best example, but the grouping may be otherwise arranged as may be desired.

75 In operation, the admission of steam to the cleaning elements directs powerful jets into the fire tubes toward the outlet ends thereof and blowing toward such ends, so as to induce through each fire tube a strong draft of combustion gases or air, or a mixture thereof, the effect of which is to dislodge and blow out any ashes, dust, soot, scale or clinkers that may be within the tubes. The operation may be performed either with the fire door (or ash pit door) 80 open or closed. In case all the cleaner nozzles are blown simultaneously, it is preferable to have such door open, whereby to admit a copious rush of air through the tubes. While the cleaner is in operation a 85 very violent induced draft is created, and unless such door is open there may be insufficient air available to thoroughly clean the boiler. If, however, the cleaner is built in two or more groups or sections, as described with reference to Fig. 2, then the 90 better way to clean the tubes is to blow each section separately. Assuming the arrangement shown in Fig. 2, this results in a powerful induced blast in the tubes on one side of the boiler, in intensification of the 95 normal draft, while in the tubes on the other side of the boiler where the nozzles are not blowing, there may be set up a back suction which will exceed and overcome the 100 normal draft. This will commonly occur 105 if the fire or ash pit door is not opened, which is the best condition for so operating the apparatus when thus built in sections. After the nozzles in one group of 110 tubes have been thus blown, the steam should be shut off from such group and admitted to the nozzles of the other group so as to blow the tubes on the other side 115 of the boiler. When thus operated, as either group of tubes is being blown, there is a forward blast (with the draft) in such tubes, and a backward suction (against the 120 draft) in the other group of tubes, thereby occasioning a circulation in lateral direction. This circulation is alternated at each 125 change from one group to the other; there results in each tube a blast, first in one direction and then in the opposite direction, whereby any adhering particles of soot or 130

scale are more effectively dislodged and expelled than if the flow were to occur in one direction only. In any case, however, if sufficient cleaning is not attained with the fire door and ash pit door closed, these doors, or one of them, may be opened so as to admit an adequate inflow of fresh air.

The inventive ideas herein set forth may receive other embodiments than those herein specifically illustrated and described.

What is claimed is:

1. In a boiler, the combination with a fire tube system of a cleaner comprising an expanding jet nozzle inserted permanently within a tube and adapted under pressure to direct a jet of fluid at high velocity parallel with the axis of the tube and in the direction of the normal draft to induce an intensified gaseous flow through the tube, and means for admitting and conducting such fluid to the nozzle.

2. The combination with a multiple fire tube boiler of cleaning means comprising expanding jet nozzles inserted permanently within the fire tubes and each adapted under pressure to direct a jet of fluid at high velocity parallel with the axis of the tube and in the direction of the normal draft to induce an intensified gaseous flow through the tube, and means for admitting and conducting such fluid to the respective nozzles.

3. The combination with a fire tube boiler of a cleaner comprising a jet nozzle inserted within a tube, toward the outlet end thereof, and means for admitting and conducting fluid under pressure to such nozzle, the nozzle having an expanding passage adapted to direct a jet of such fluid at high velocity parallel with the axis of the tube, and in the direction of the normal draft, whereby to induce a gaseous blast throughout the length of the tube, whereby to clean the entire length of the tube by means of such induced blast.

4. The combination with a multiple fire tube boiler, of cleaning means comprising jet nozzles mounted in the tubes thereof, near the outlet ends of such tubes, and directed toward such ends so as to project jets in the direction of the draft, such nozzles having an expanding passage adapted to direct such jets at high velocity parallel with the axis of the tubes to induce a gaseous flow or blast through the length of the tubes to clean the same, and means for admitting and conducting fluid under pressure to such nozzles.

5. The combination with a multiple fire tube boiler of cleaning means therefor comprising expanding jet nozzles located in such tubes near their outlet ends, adapted to direct jets parallel with the axes of the tubes toward such outlet ends, and means

for admitting and conducting fluid under pressure to such nozzles, comprising pipes in the smoke box beyond such tubes, and branch pipes leading therefrom into the respective tubes and terminating in reverse elbows communicating with the respective nozzles, such pipes, nozzles and elbows being of small cross-section relatively to that of the tubes, so that they may be mounted permanently therein without obstructing the normal draft therethrough.

6. The combination of claim 5 with holding means for supporting said piping and bracing it against the reactive thrust of the jets from the nozzles.

7. The combination of claim 5 with holding means for supporting said piping and bracing it against the reactive thrust of the jets from the nozzles, such holding means comprising a part fastened to said pipes and bearing against the boiler tube sheet.

8. The combination with a fire tube boiler having two series or groups of fire tubes, of cleaning means for one such series or groups, comprising pipes permanently located within the tubes thereof having nozzles directing jets within the tubes parallel thereto, and in the direction of the normal draft, and a valved conduit conducting fluid under pressure to such pipes and nozzles whereby when fluid under pressure is admitted thereto the jets from the nozzles induce an intensified gaseous flow through the fire tubes of said group in the direction of the normal draft, accompanied by a reverse flow of gases through the tubes outside such group.

9. The combination with a fire tube boiler having two series or groups of fire tubes, of two series or groups, of cleaning means comprising pipes permanently located within said tubes having nozzles directing jets within the tubes parallel thereto, and in the direction of the normal draft, whereby to induce an intensified flow of gases through the tubes, and conduits conducting fluid under pressure to the respective groups of cleaning means, with valves for controlling the flow thereof to either group separately, whereby when fluid is admitted to one group of cleaning means, the jets from the nozzles thereof induce a gaseous blast in corresponding direction through the fire tubes of such group, accompanied by a reverse flow of gases through the tubes of the other group, and when fluid is shut off therefrom and admitted to the other group of cleaning means, the gaseous flow through the respective groups of fire tubes is reversed.

In witness whereof, we have hereunto signed our names.

FREDERICK W. LINAKER.
THEODORE M. BRUBACK.
